METHOD OF AND MEANS FOR CLEANING
MATERIALS

Charles Calvert Lamb, Chicago, Ill.

Application September 6, 1932, Serial No. 631,809

15 Claims. (Cl. 68—38)

The invention relates to a method of, and means for cleaning materials such as fabrics, furs, leather and similar materials, and its principal object consists in providing a novel method of, and means for, cleaning materials in a safe, sanitary, expeditious and yet efficient manner.

It is a further object of the invention to provide a novel method of, and means for, cleaning materials in an inexpensive, rapid manner without sacrificing efficiency of the cleaning process.

It is a further object of the invention to provide a novel method of, and means for, cleaning materials, whereby a cleaning fluid of high or low flash point may be used without entailing any danger of combustion or explosion.

It is a further object of the invention to provide a novel method of, and means for, cleaning materials whereby the cleaning fluid is brought in contact with the material to be cleaned under the exclusion of any gasifying or vaporizing media, whereby the cleaning process might be impaired or defeated.

It is a further object of the invention to provide a novel method of, and means for, cleaning materials wherein during the entire cleaning process the original volume of cleaning fluid is maintained or preserved, enabling thereby repeated use of the cleaning fluid for subsequent cleaning processes.

A further object of the invention aims at providing a novel method of, and means for cleaning materials wherein the cleaning fluid is prevented from vaporizing or gasifying, so that during any stage of the cleaning process the action of the fluid in removing impurities, greases or other contaminations is maintained at the highest degree of efficiency.

It is also an object of the invention to provide a novel method, and means for cleaning materials to prevent the fluid from reaching its saturation point, enabling thereby repeated use of the fluid, before being returned for reclaiming.

It is still a further object of the invention to provide a novel method of, and means for enabling the fabric to be sprayed or rinsed under centrifugal force.

It is also an object of the invention to provide a container for the reception of articles to be cleaned, which has an opening and egress ports, which container is journaled in a casing to execute an oscillatory movement with the casing and an independent rotary movement, said opening and ports being closed during oscillation and open during rotation.

It is a still further object of the invention to provide a self-contained reservoir in the apparatus to enable the fluid to be retained intact in the apparatus after the cleaning process, and to permit the fabrics to be sprayed and rinsed under centrifugal force, and the rinsing medium to be removed from the apparatus again under centrifugal force without coming in contact with the cleaning fluid in the reservoir and subsequently to return the fluid into the container under gravity preparatory to the next cleaning process.

It is also an object of the invention to provide certain details of construction and arrangement tending to enhance the efficiency and utility of an apparatus of the character described.

With these and other equally important objects in view which will become apparent from a perusal of the invention, the latter comprises the means and novel steps described in the following specification, particularly pointed out in the claims forming a part thereof, and illustrated in the accompanying drawings, in which

Fig. 1 is a top plan view of an apparatus constructed in accordance with my invention, parts being shown in section to disclose interior construction.

Fig. 1a is a fragmentary detail view of a tube for the ingress of air.

Fig. 2 is a side view of the apparatus.

Fig. 3 is a front elevational view of the apparatus.

Fig. 4 is a section on the line 4—4 of Fig. 1.

Fig. 5 is an elevational section through a casing and container which is slightly modified.

Fig. 6 is a detail view of a valve.

Fig. 7 is a horizontal section through a further modification of the container.

Fig. 8 is a detail view of a bearing plate secured to the casing.

Fig. 9 is a section through a door in the casing controlling an opening in the container, and

Fig. 10 is an elevational section through another modification of the container.

The machine comprises a base plate 10 of oval shape which at the edge is curved downwardly as at 11 to afford stability to the machine supported on said plate. To the base plate is secured in any approved or convenient manner a housing

12 also of oval shape and made up of sections 12a, 12b and 12c in superposed relation and secured together by lugs 12d and screws 12e to

provide a housing of desired height to afford protection against contact with moving parts of the

machine and to afford a support for the main shaft of the device.

To this end the housing section 12c is provided at the left side as viewed in Fig. 1 with a bearing 5 block 13 provided with a semi-circular recess and having a top 14 formed with a similar recess to surround a hollow shaft 15 projecting at right angles to the longitudinal axis of an oval outer casing 16 comprising two sections bolted together 10 as at 16a (Fig. 3). At the opposite side the casing 16 has a solid shaft 17 journaled in a split bearing 18 formed integral with the housing section 12c. The bearing 18 has an extension 19 terminating in an integral split bearing 20 15 in which is journaled a stub shaft 21 constituting the drive shaft for actuating the machine forming the subject matter of the invention. A horizontal bracket 22 projects from the housing section 12c and has pivotally secured thereto 20 the intermediate portion of a shift lever 23 provided at the free end with a handle 24 and terminating at the other end in a yoke 25 connected with a clutch sleeve 26 adapted to couple shafts 21 and 17 or to release shaft 17 depending on 25 the position of the sleeve caused by actuation of the lever 23.

The stub shaft 21 has secured to its outer end a hub 26 by a cross-pin 27, and integral with said hub is a depending arm 28 which continues 30 downwardly equi-distant from the extension 19, and the housing 12 to terminate in a gear sector 29 concentric to the stub shaft 21 and in mesh with a rack 30 slidably supported in a bracket 31 secured to the housing section 12a by screws 35 or by any other conventional or approved means.

The rack 30 is connected to a pitman 32 whose other end is pivotally connected to the side of a worm wheel 33 by a pin 34 arranged in a casing 35 integral with the housing section 12a. The 40 worm wheel is in mesh with a worm 36 fast on a shaft 37 of a motor 38 secured to the base plate 18. From the foregoing it is obvious that upon 45 running of the motor 38 the gear 33 by the pitman 32 will impart a reciprocating motion to the rack 30 causing oscillation of the sector 29 and therewith of the stub shaft 21, which motion may be transmitted to the shaft 17 and outer casing 16 for a purpose hereinafter further explained.

The outer casing 16 surrounds an inner container 39 which is concentric to the outer casing and throughout its periphery maintains an equal 50 distance from the outer casing, except at the apex.

The inner container is supported in bearings 55 40 and 41 provided in the apexes of the outer casing 16 and thus the bearings are in longitudinal alignment at right angles to the axis of oscillation of the outer casing.

The bearing 40 comprises a tubular member 42 closed at the inner side by a wall 43 and having an opening 44 for the passage of a tube 45 integral with the apex of the inner container 39 and projecting past the opening 44 and through the bearing 40 to temporarily receive an elbow 46 of a pipe 47 provided with a valve 48, which pipe leads to a source of fluid supply adapted to be used for the cleaning or dry cleaning of fabrics arranged in the inner container 39. The bearing 40 has packing rings 49 and 50 abutting the wall 43 and a radial and end thrust bearing 51 covered by a ring 52 having press fit with the bearing. The bearing 41 is constructed similarly to bearing 40 and supports for rotation a solid stud 53 projecting from the apex of the

inner container 39 and passing through the bearing 41. A supporting collar 54 maintains the stud 53 and thereby the inner container 39 against displacement in downward direction.

The tube 45 is in communication with the inner container 39 by an opening 55, constituting a valve seat and controlled by an automatic valve 56 whose stem 57 projects past the outer end of the tube 45 so that upon applying the pipe 47 to cause inflow of the cleaning fluid a 10 lug 58 of the elbow 46 forces the stem 57 inwardly to open the valve 56 against the pressure of a spring 58 provided in the tube 45 and contacting at one end with a perforated partition 59 and at the other end with a collar 60. The valve stem 57 is guided in its reciprocating motion by the perforated partition 59 and an additional perforated partition 61.

The inner container 39 is made up of two shells 60' and 61' of suitable material which complement each other to form a complete oval container.

The shells 60' and 61' are formed at the inner ends with a circumferential flange 62 provided with a circular series of holes 63 for the passage of bolts to secure the shells together after a packing gasket 64 of cork, rubber or other suitable packing material has been interposed between the flanges 62. Ports 65 are provided in said gasket at equal intervals around the entire circumference of the gasket.

Attention is called to the fact that the shell 61' is slightly longer than the companion shell 60' in order to cause junction of the shells to be situated to one side of the transverse center 35 of the outer casing 16, where the outlet for the fluid is provided as hereinafter further explained.

A spring band 66 surrounds the gasket 64 (Fig. 1) arranged between flanges 62 and is held in position by means of guide pins 67, secured in 40 appropriate manner to the casing.

The band 66 at the upper side is open and its ends are provided with gibs 68 controlled by a pair of tongs 69 pivotally secured to a pin 70 and extending through a slot 71 in the outer casing 16 to contact with said gibs. The tongs are partly received in a closed casing 72 secured to the outer casing 16 by bolts 73. The casing has an adjusting screw 74 which extends through the wall of casing 72 and is held 50 against longitudinal movement by washers 75 which also seal the opening against leakage. A yoke 76 is arranged on the screw 74 which upon rotation, respectively, causes lowering or raising of the yoke whereby the tongs are either compressed or expanded to close or open the band and consequently the ports 65.

The outer casing 16 is formed with a circumferential trough 77 to divert fluid into the hollow shaft 15 which fluid aggregates at the center of 60 the container under centrifugal force, and thence escapes through said shaft and a pipe 78 controlled by a valve 79 (Fig. 3) to a receptacle (not shown) or back to the source of supply. The shaft 15 is also in communication with a pipe 65 80 provided with a valve 81 and having atmospheric communication for the egress of a current of fresh air from the inner container while rotating about its longitudinal axis after all cleaning fluid has been removed, so as to cause 70 the removal of any trace of odor that may be left in the articles. The air current or, if desired a fluid, is admitted through a tube 82 fitting over the bearing 40 (Fig. 1a) and its lug 83 opens the valve 56 permitting air or fluid to flow past said 75

valve into the container 39 and the air or fluid is removed through the ports 65 into the interspace between the outer and inner containers 16 and 39, respectively.

5 Fan blades 84 secured to the tube 45 and the stud 53 set up eddy-currents and cause the air or fluid to escape through the shaft 15 and pipe 80 to the atmosphere. Of course at that time the valve 81 is open and the valve 79 is closed.

10 Rotation is imparted to the inner container as follows:

The motor shaft 37 is provided with a grooved pulley 85 which is in alignment with a pulley 86 fast on a stub shaft 87 supported in bearings 88

15 upstanding from the base plate 10 (Fig. 3). A belt 89 is trained around pulleys 85 and 86.

The inner end of the stub shaft 87 is provided with a helical pinion 90 adapted to mesh in true pitch line with a mating helical gear 91 secured 20 to the stud 53 when the inner container is in vertical position (Fig. 3) for extracting purposes.

In such position the outer casing is held locked (as shown in Fig. 3) by a pin 92 entering a recess 93 in housing section 12c (Fig. 2) and locked 25 therein by a dog 94 against displacement.

To introduce the fabric into the inner container 39 through the outer casing 16 a door generally designated by 95 is provided (Fig. 9) which is hingedly secured to the outer container as at 30 96. The door 95 engages with an upstanding flange integral with the outer casing there being a packing gasket interposed between said flange and said door to insure hermetic sealing. The door is provided with an inwardly projecting tubular member 96 of round or oblong cross section and is telescopingly fitted in an upstanding tubular flange 97 conforming to the contour of the flange 96 but smaller than the opening 98 which the door 95 covers. The flange 97 is integral 35 with a second door 99 closing an opening 100 in the inner container by engagement with a flange 101 with the interposition of a sealing gasket 102 to hermetically seal the container during the cleaning process. The door 99 has an upstanding sleeve 103 in which enters the stem of an adjusting screw 104 held against longitudinal movement by washers 105 which seal the opening for the passage of the screw.

By means of this door it is possible to hermetically close the inner container so that no leakage or seepage occurs during the cleaning process while the container is being oscillated.

To rotate the inner container it is necessary to release the same by adjusting the door 99 to 55 release the flange 101, and yet no noxious gases are permitted to escape into the room to harm the operator, as the centrifugal force set up by the rotation of the inner container causes the fluid to flow toward the center of the apparatus 60 between the two containers and there to escape through the hollow shaft 15.

In operation, the casing 16 and the container 39 may be arranged either in horizontal position or in vertical position for the purpose of permitting fabrics to be introduced into the inner container for cleaning.

To this end, the door 95 is swung into open position, the second door 99 being so dimensioned as to easily pass the opening 98 in the container 16.

70 After introducing the fabrics and closing and locking the outer door 95 by means of a dog 106 so that casing 16 and container 39 are hermetically sealed, the inner door is secured in 75 tight engagement with the inner container by

actuation of the adjusting screw 104. Thereupon, the adjusting screw 74 is actuated to close the band and the ports 65 to further hermetically seal the inner container.

After the pipe 47 has been applied and the valve 56 opened, the valve 48 is opened to permit ingress of the fluid into the inner container. Then the pipe 47 is detached, whereby the valve 56 is closed so as to completely and hermetically seal the inner container against the escape of 10 fluid. If the casing and container are in vertical position they are placed in horizontal position, and the shift lever 23 is actuated to impart oscillatory movement to the shaft 21.

Oscillation of the shaft entails oscillation of 15 both the outer casing and inner container through the agency of the rack 30 and sector 29.

After the fabrics are thoroughly cleansed, the casing and container are placed in vertical position and locked by the agency of the dog 94. 20 Then the valve 79 is opened and the inner door 99 is released by actuating the screw 104 to disconnect the inner casing from the outer container and enable free rotation of said inner container. Subsequently the adjusting screw 74 is 25 actuated to release the band 66 and permit passage of the fluid through the open ports 65.

Fluid can then pass out through the pipe 78 under the centrifugal force of the inner container which is being rotated by virtue of the 30 engagement of its pinion 91 with the pinion 90.

The fluid is then removed to a receptacle or to the source of supply, as the case may be. After removal of the fluid, the valve 79 is closed, the pipe 82 is placed over the tube 45 and bearing 40 35 to open the valve 56 to permit fresh air or fluid to ingress into the container and to sweep through the interval between the casing and container aided by the centrifugal force set up by the rotation of the inner container and the fan blades and 40 escapes through the shaft 15 into the pipe 80 after the valve 81 has been opened to egress into the atmosphere. The rotation of the fan blades at that time sets up eddy-currents aiding in sweeping the air or fluid from the outer container into 45 the shaft 15, so that when the said door, 95 is opened, all gases are completely scavenged out of the machine and no noxious gases remain either in the machine or in the cleaned fabrics, tending to 50 harm or injure persons operating the machines.

The modification shown in Fig. 5 is in all respects identical with the embodiment described in connection with Figs. 1 to 4, inclusive, except that the inner container 39' is made of glass or other 55 non-corrosive material.

The tube 45' is connected to the inner container 39' simultaneously when the latter is being molded. To this end, the tube 45' is provided with lateral lugs 105', which are imbedded in the apex of the inner container to be functionally integral with said container and to be anchored against longitudinal displacement.

The modification shown in Fig. 7 is distinguished from the previously described modifications in that the inner container 39'' consists only of a lower shell, while the upper shell is omitted, and the outer casing 16' is provided with an annular shoulder 106 forming a seat for the upper edge of the inner container shell, and having 60 means for preventing displacement of said inner container while in rotation or during oscillation.

The outer casing is provided on the inside with an upwardly extending flange to form a trough 70' and the container has a plurality of ports 65'.

which may be opened or closed by a spring band 66'.

Cleaning liquid is introduced through the valve 56' and enters the container 39''. Upon turning 5 the container 180° the fluid escapes through the open ports 65' while the extractor is rotated. The trough 77' directs the fluid to the hollow shaft 15' whence it escapes back to the source of supply (not shown) by opening the valve 79'.

10 Upon opening the valve 80' air may be introduced through the valve 56' to remove traces of noxious gases.

The hollow shaft 15' and the solid stud 21' are each provided with a bearing plate 107 which is 15 secured to the outer casing 16' by a plurality of screws 108.

The modification shown in Fig. 10 is distinguished from the first described modification by the manner of supporting the inner container to 20 permit simultaneously rotation and oscillation thereof, so that no vibration is imparted to the outer structure of the machine.

As shown, the inner container 111 is supported at one end with an adjustable socket 112 having 25 pins 113 entering holes in the wall of the casing 114. An adjustment screw 113' held against longitudinal movement in a hub 115 of the casing 114 enters with its stem in the socket 112.

At the other end of the container its end wall 30 116 is formed with an opening 117 to encompass a ball 118 of a valve housing 119 containing a valve 120 controlling the admission of fluid. The valve housing 119 is supported in a bearing 121 and is equipped at the upper end with a helical 35 wheel 122 meshing with a helical pinion 123 fast on a shaft 124 supported in a bracket bearing 125 secured to the standard 126 of the machine frame. A pulley 127 fast on the shaft 124 is belted to the pulley 128 fast on the stub shaft 129. When the 40 container is to be oscillated and rotated at the same time, then the socket 112 is withdrawn from contact with the inner container 111, so that the latter is suspended from the ball 118 and can execute both an oscillatory and rotary movement.

45 Oscillation is imparted by the depending arm 28 and the gear sector 29 which meshes with the rack 30, the same as has been described in connection with the first described embodiment. The container is locked against rotation by the socket 112, after adjusting the screw 113' so that the casing 114 can only oscillate in unison with the container. After the material in the container 111 has been cleaned and the machine is turned in vertical position as shown in Fig. 10, the screw 55 113' is adjusted to release the container 111 leaving it suspended on its ball support 117.

If there is any overload or unequal distribution of the load the container will vibrate during rotation but will not permit such vibration to be 60 transmitted to the casing or entire structure of the machine.

While the drawings show preferred embodiments of the invention, numerous changes and alterations may be made without departing from the spirit of the invention. I, therefore, do not limit myself to the details of construction and arrangement of parts, as shown, nor to the sequence of steps of the method, as described, but claim my invention as broadly as the state of the art permits.

I claim:

1. In a machine of the character described, an inner container, an outer casing surrounding said inner container, means for continuously oscillating said container and said casing in unison about

a common axis, and means for rotating said container about an axis at right angles to said common axis.

2. In a machine of the character described, a container, a casing surrounding said container, a door in said casing controlling an opening in said container, means for continuously oscillating said container and said casing in unison about a common axis, and means for rotating said container only in a predetermined position about an axis at 10 right angles to said common axis.

3. In a machine of the character described, an oval container having an opening, a casing concentrically surrounding said container, a door on said casing, means on said door to seal said center opening, means for oscillating said container and said casing about a common transverse axis, and means for rotating said container only about its longitudinal axis.

4. In a machine of the character described, 20 a container, a casing concentrically surrounding said container and supporting the same, means for admitting a fluid to said container, means for permitting egress of said fluid, said container being normally hermetically sealed, 25 means for continuously oscillating said container and said casing about a common transverse axis, and means for rotating said container only about its longitudinal axis.

5. In a machine of the character described, a 30 container having an inlet opening and outlet ports, a casing surrounding said container and supporting the same, means actuated extraneously to said casing for sealing said ports in said container and releasing the same, means for 35 sealing said opening, means for continuously oscillating said container and said casing about a common transverse axis, and means for rotating said container about its longitudinal axis.

6. In a machine of the character described, a 40 container having an inlet opening, a casing surrounding said container and rotatably carrying the same, means on said casing for closing said inlet opening and thereby rigidly connecting said container and casing, means for oscillating said 45 container and said casing about a common transverse axis, and means for rotating said container about its longitudinal axis after release of its inlet opening.

7. In a machine of the character described, a 50 casing, a container journaled with axially aligned studs in said casing, means for continuously oscillating said casing and said container about an axis transverse to said studs to prevent the formation of gases in the head room, and means 55 for rotating said container only about its studs.

8. In a machine of the character described, a 60 casing, a container journaled at its ends in said casing and having circumferentially arranged ports, means adapted to close and open said ports, means extraneous to said casing for actuating said first named means, means for oscillating said casing and said container about a common axis, and means for rotating said container about an axis at right angles to said common axis.

9. In a machine of the character described, a 65 casing, a container journaled at its ends in said casing and having an inlet opening and a series of ports, a spring band actuated extraneously to 70 said casing sealing said ports, means for oscillating said casing and said container in unison, and means for rotating said container.

10. In a machine of the character described, a 75 casing, a container journaled at its ends in said

- casing and having an inlet opening and a series of outlet ports, a spring band actuated extraneously to said casing for covering and sealing said ports, a door on said casing admitting access to said inlet opening and sealing the same, respectively, means for admitting a fluid into said container, and means for exhausting the fluid under centrifugal force.
11. In a machine of the character described, a casing, a container journaled at its ends in said casing and having an inlet opening for articles to be introduced and a series of outlet ports, a spring band actuated extraneously to said casing for covering and sealing said ports, a door on said casing affording access to said inlet opening and sealing the same, respectively, means for selectively introducing fluid and air to said container, means for oscillating said casing and said container in unison, and means for exhausting the fluid and the air under centrifugal force.
12. In a machine of the character described, a casing, a container journaled at its ends in said casing and having an inlet opening and a series of ports, a spring band actuated extraneously to said casing and encompassing said container for closing and uncovering said ports, a door on said casing affording access to said inlet opening and sealing the same, respectively, said casing having an opening adapted to communicate with said ports, means for oscillating said casing and said container in unison, and means for rotating said container independently of said casing.
13. In a machine of the character described, a casing, a container surrounded by said casing, means for suspending said container from said casing for universal movement, means for releasably locking said container against rotation, means for oscillating said casing and said container in unison, means for rotating said container, and a means enabling said container to vibrate during said rotation.
14. A method of cleaning materials, comprising the steps of introducing materials into a perforated container, sealing said container, introducing a volatile fluid into said container, maintaining said fluid in a non-gaseous state during the cleaning process by continuously co-mingling the fluid and evolved gases, subsequently opening said container, and removing the fluid from the materials and the container under centrifugal force by rotating the container.
15. A method of cleaning materials, comprising the steps of introducing materials into a perforated container, sealing said container, introducing a volatile fluid into said container, maintaining said fluid in a non-gaseous state during the cleaning process by continuously co-mingling the fluid and evolved gases, subsequently opening said container, removing the fluid from the materials and the container under centrifugal force by rotating the container, and eliminating odor and traces of said fluid from the materials.

CHARLES CALVERT LAMB.
